UNITED STATES PATENT OFFICE.

WILLIAM COLE, OF IRONWOOD, MICHIGAN, ASSIGNOR TO THE COLE-GOUDIE SHOVEL COMPANY, OF IRONWOOD, MICHIGAN, A CORPORATION OF MICHIGAN.

PNEUMATIC SHOVEL.

1,321,983.

Specification of Letters Patent. Patented Nov. 18, 1919.

Application filed March 31, 1919. Serial No. 286,338.

To all whom it may concern:

Be it known that I, WILLIAM COLE, a citizen of the United States of America, residing at Ironwood, in the county of Gogebic and State of Michigan, have invented certain new and useful Improvements in Pneumatic Shovels, of which the following is a specification.

The present invention relates to improvements in pneumatic shovels, designed especially for excavating or shoveling rock, stone, etc., for loading on cars, and as the implement occupies a minimum amount of head room and comparatively small radius of rotation, it is especially adapted for shoveling and loading on mine cars the coal broken down by blasting in underground mining operations, thereby permitting its free use within the confines of mine drifts or openings.

The primary object of the invention is the provision of an implement of this type which possesses simplicity in both construction and operation and is adapted for operations in small compass, is comparatively light in weight, and may be manipulated with facility so that it is flexible and simple under control of the operator.

To this end the invention consists in certain novel combinations and arrangements of parts involving the utilization of a pair of co-acting, angularly disposed motive fluid pistons and their cylinders mounted upon a rotary support, and in certain other devices in combination therewith as will be herein-after pointed out and claimed.

In the accompanying drawings I have illustrated one complete example of the physical embodiment of my invention, constructed and arranged according to the best mode so far devised for the practical application of the principles of the invention.

Figure 1 is a view in side elevation, partly in section, illustrating an implement or pneumatic shovel constructed according to the invention.

Fig. 2 is an elevation taken at right angles to the view of Fig. 1, parts also being shown in section.

Fig. 3 is a plan view, showing a part of the rotary support in section, and illustrating in dotted lines the lateral swinging movement of the shovel.

Fig. 4 is a plan view of the rotary platform showing the upright side plates of the frame in section.

Fig. 5 is a detail sectional view, enlarged showing the ball bearings between the rotary base of the frame and the fixed casting or circular plate on the truck.

Fig. 6 is a perspective view showing in detail one of the links by which the implement is anchored to the rail of the track upon which the truck is rolled.

While I shall hereinafter refer to the implement as a pneumatic shovel, it will be understood of course that other motive fluid may be employed if found desirable, but in the present instance it is found convenient to designate the implement by the term pneumatic shovel, and it will also be apparent that other changes and alterations may be made within the scope of my claims without departing from the spirit of my invention.

In the preferred form of the invention as illustrated in the drawings, I have utilized an ordinary mine truck 1 of usual type and adapted to travel on the track rails as usual, and upon the truck is rigidly and securely fastened a circular casting or fixed base plate 2, to support the rotary portion of the implement, a central toothed gear 3 being riveted or bolted to the circular plate for engagement by the small pinion 3' indicated in Fig. 3. The circular base 4 of the revolving frame, has bearing balls 4' between it and the base plate 2 so that the rotary part of the implement may swing or rotate freely in the process of working or loading of the material to be handled.

The superstructure of the implement is supported on the two upright, stiffened frame plates 5, 5, spaced apart and bolted securely to the base 4 of the rotary frame, and the two oscillatable cylinders 6 and 7 are pivoted or journaled in these plates, the piston rod 8 of the cylinder 6 being connected by a clevis or forked shaped yoke 9 to the bucket or shovel 10 by the bearing pins 11. The rod 8 has the usual piston or head 12 and the cylinder has the ports 13 and 14 at its ends for the admission and exhaust of motive fluid. The shovel 10 which is in the usual form of a bucket is swiveled on the pins 11 and has a limited

swinging movement between the two angle plates 15 with which the clevis 9 will contact to prevent excessive movement of the shovel.

- 5 At the point 16 in Fig. 1 it will be seen that the piston rod 17 of the air cylinder 7 is pivoted to the air cylinder 6, so that in conjunction with the motor 18 which is the prime mover through the pinion 3' and the 10 fixed gear 3 for rotating the superstructure of the implement, the cylinder 6, together with a rotary electric its piston rod and shovel, may be made to oscillate in the bearing blocks 19 on the pair of diametrically 15 opposed trunnions 20 of the cylinder 6. These bearing blocks are supported in the upright side plates of the frame, and in Fig. 2 it will be apparent also that the shorter cylinder 7 is also oscillatably supported in 20 the side plates by its blocks 19' and its trunnions 20' the former being attached to the side plates 5.

Motive fluid is furnished to the implement through the air pipe 21 which is fixed and 25 supported in the plates 5 and is furnished with branch pipes 22, 23, 24, the latter being connected as a supply or feed pipe for the motor 18. The branch pipe 22 is connected to the flexible pipe or air hose 25 of 30 the cylinder 6 which communicates at both sides of the piston through the ports 13 and 14, while the branch pipe 23 communicates with the flexible pipe or hose 26 that communicates with the cylinder 7 through the 35 two end ports 27 and 28 of that cylinder.

The action of the piston in cylinder 6 is under control of the valve lever 29 of the fourway cock 30, and the action of the piston in cylinder 7 is under control of the lever 40 31 of the fourway cock 32, and the admission of air to the motor 18 may be controlled in any suitable manner, the controlling device being located in position accessible for and convenient to the operator or attendant who 45 manipulates the levers 29 and 31.

In Figs. 1 and 6 means are illustrated for anchoring the implement with respect to the rail R which means comprise an open link 22' at each of the four corners of the truck, 50 pivoted in the metal strap 23' and the open ends of the link, as 24' are made to clasp the rail by means of the clasp-link 25' which may be forced down on the bars of the open link to clasp the rail at its free end.

55 The shovel or bucket is illustrated as equipped with a hinged bottom 23* that may be latched and unlatched in any of the usual or suitable ways, and the truck may be moved along on its rails in suitable manner, 60 as well understood.

In operation air is admitted to either side of the piston 12 in its cylinder 6 through the ports 13 and 14 by proper manipulation of the lever 29, and air is admitted to either

side of the piston 17' in the cylinder 7 65 through its ports 27 and 28 by manipulation of the lever 31. By manipulation of the lever 29 the dipper or shovel may be extended into the pile of material to be moved, and then by manipulation of the lever 31 the piston 70 rod 17 is projected so that the cylinder 6 swings on its trunnions to scoop up the material, the cylinder 7 also swinging on its trunnions to compensate for the movement of the cylinder 6, and the scooping action 75 of the shovel on the material is accomplished by a combined manipulation of the two cylinders. When the shovel has scooped up a load it is withdrawn to the loaded position 80 indicated in Fig. 1, and then through power 85 from the motor 18 the superstructure of the implement is rotated on the circular base plate and its ball bearings, to position with the shovel at the rear of the implement and within easy access of the car to be loaded from the shovel. The loaded shovel is then 90 raised to the dotted position in Fig. 1 through the action of the motive fluid admitted below the piston 17' in the cylinder 7, and while in the horizontal position indicated the piston rod 8 with the shovel may be projected over the car to be loaded, and the hinged gate or bottom 23* of the shovel is tripped to dump the material in 95 the car to be loaded. The reversal of this operation just described returns the shovel to digging or excavating position again, and the implement is held stable during the working operations by the shackles or clasp links 22'.

From the above description taken in connection with the drawings it is evident that the implement may be used for loading or for excavating and loading material, either underground or for surface work, and as the 105 whole structure is compact and contained within small compass it may readily be taken into and through any mine or tunnel opening for operations, and there be worked with efficiency and economy.

What I claim is:

1. The combination with a rotatable support including a pair of spaced uprights, of a piston cylinder pivoted adjacent to one end between the upper portions of said uprights, a piston therein having its rod projecting exteriorly through the opposite end of the cylinder, a shovel pivoted directly upon the outer end of said rod, a second cylinder pivoted between the uprights below the first cylinder, a piston therein, and a rod extending from said piston exteriorly through one end of the second cylinder and pivotally connected to the first cylinder between the pivot of the latter and its outer end.

2. The combination with a rotatable support including a pair of spaced uprights, of a piston cylinder pivoted adjacent to one

end between the upper portions of said uprights, a piston therein having its rod projecting exteriorly through the opposite end of the cylinder, a shovel pivoted directly upon the outer end of said rod, a second cylinder pivoted at a point intermediate its ends between the said uprights and below the

first cylinder, and a piston in the second cylinder having a rod projecting exteriorly through the outer end of the cylinder and 10 pivotally connected to the first cylinder.

In testimony whereof he affixes his signature.

WILLLIAM COLE.
